COMBINED SHIRT AND SUSPENDERS

Peter M. Bambino, San Francisco, Calif.

Application March 30, 1935, Serial No. 13,949

3 Claims. (Cl. 2—117)

This invention relates to improvements in garments and has particular reference to a combined shirt and suspenders.

The principal object is to produce a garment which to all intents and purposes is a conventional garment such as a shirt, and to incorporate in the construction of the shirt, a suspension device which is concealed which is a part of the garment, and yet a device which will permit the securing of the trousers and the supporting of the same in a most efficient manner.

A further object is to produce a device which will not interfere with the laundering of the garment.

Another object is to produce a device which is economical to manufacture and one which is so designed that it will not in any way cause undue strain upon the garment.

A still further object is to produce a device which is comfortable to wear and one which will not be unsightly in use.

Other objects and advantages will be apparent during the course of the following description.

In the accompanying drawing forming a part of this specification and in which like numerals are employed to designate like parts throughout the same,

Fig. 1 is a front view of a shirt constructed in accordance with my invention,

Fig. 2 is a side elevation of Fig. 1 on a reduced scale,

Fig. 3 is a perspective view of the suspender portion of my device,

Fig. 4 is a fragmentary detail view showing the manner in which a hook may be secured to a pair of trousers,

Fig. 5 is a perspective view of the hook and connection with the suspender, and

Fig. 6 is a fragmentary view of the shirt in open position, showing the manner in which the suspender is stitched within the collar and beneath the yoke of the shirt.

It is common practice to wear invisible suspenders, which are merely a separate pair of suspenders worn between the ordinary shirt and ordinary underwear. With some styles of underwear the suspenders rub upon the flesh, are uncomfortable and at best are unsanitary and also cause holes in the sides of the shirt where the buckle engages the customary suspender button of the trousers. Applicant, therefore, has designed a shirt wherein a suspender is formed as a part of the shirt, which suspenders have a loop extending through eyelets in the side of the shirt,

which loop may engage the suspender buttons of the trousers or hooks substituted therefor. Applicant's suspender is preferably made of a light material, similar to the shirt goods and therefore a material which will easily launder when the shirt is washed and a material which will not interfere with the easy ironing of the shirt.

In the accompanying drawing wherein for the purpose of illustration is shown a preferred embodiment of my invention, the numerals 5 and 6 designate the two front portions of an ordinary shirt having the customary collar band 7. At 8 and 9 I have shown openings through the shirt which form eyes through which the loops 11 and 12 of the suspenders are threaded. The suspender consists of a light weight webbing 13 having its end portion extending along the front of the shirt and toward the sides thereof and provided with button holes 14 and 16. This webbing 13 is stitched to the shirt in such a manner that a portion thereof lies within the collar band 7 (see the portion A Figs. 1 and 6). The webbing is also stitched between the double cloth of the yoke as indicated in Fig. 6. The ends having the button holes 14 and 16 extend downwardly along the front of the shirt as shown at B in Fig. 2. Attached to the webbing 13 near its medial line are back straps 17 and 18. These back straps have button holes 19 and 21 formed in their ends so as to receive the knotted ends of the loops 11 and 12. The loops 11 and 12 may be shortened or lengthened by simply forming a new knot which will not slip through the button holes and makes a most simple manner of adjusting the loops.

It is here pointed out that all of the strain is carried to the point A of the shirt and as this is the focal point from which the body movements start, it will be apparent that practically no strain will be placed upon the garment, other than that of supporting the trousers. In other words, the wearer will be free to move in any desired direction without feeling any pull upon his suspenders.

In Figs. 4 and 5 I have shown fragmentary portions of trousers at 22 to which a hook 23 is attached. This is merely a substitute for the ordinary suspender button commonly found on trousers.

It will thus be seen that I have produced a shirt together with a pair of suspenders as a unitary garment, which garment will perform all the objects above set forth.

It is to be understood that the form of my invention herewith shown and described is to be taken as a preferred example of the same and that various changes relative to the material,

size, shape and arrangement of parts may be resorted to without departing from the spirit of the invention or the scope of the subjoined claims.

Having thus described my invention, I claim:—

- 5 1. In a device of the character described, the combination with a shirt, of suspenders secured thereto, said suspenders including a fabric strap secured to said shirt by having its central portion lying within the neckband of said shirt and having its end portion extending down the front of said shirt and towards the side thereof, and a pair of diverging back straps secured to said fabric strap at a point within the neckband and having its extremities extending downwardly and 10 toward the sides of the shirt, and a pair of loops secured to the ends of said front portions and said back portions, said loops having their medial portion passing through eyes formed in the sides of said shirt.
- 15 2. In a device of the character described, the combination with a shirt, of suspenders secured thereto, said suspenders including a fabric strap secured to said shirt by having its central portion lying within the neck band of said shirt and having its ends extending down the front of the shirt and toward the sides thereof, a pair of diverging back straps secured to said fabric strap at a point within the neck band and having their 15 extremities extending downwardly toward the side of the shirt, and trouser engaging means connecting the ends of said straps.
- 20 3. In a device of the character described, the combination with a shirt of suspenders secured thereto, said suspenders including a fabric strap secured to said shirt by having its central portion lying within the neckband of said shirt and having its end portion extending down the front of said shirt and towards the side thereof, and a pair of diverging back straps secured to said fabric strap at a point within the neckband and having its extremities extending downwardly and toward the sides of the shirt, a pair of loops secured to the ends of said front portions and said back portions, said loops having their medial portion passing through eyes formed in the sides of said shirt, said loops being adjustably connected 10 to said front and back portions.

3. In a device of the character described, the combination with a shirt of suspenders secured thereto, said suspenders including a fabric strap secured to said shirt by having its central portion lying within the neck band of said shirt and having its ends extending down the front of the shirt and toward the sides thereof, a pair of diverging back straps secured to said fabric strap at a point within the neck band and having their 15 extremities extending downwardly toward the side of the shirt, and trouser engaging means connecting the ends of said straps.

PETER M. BAMBINO.
